Primary Examiner — W. A. Teddy Falloway

Assistant Examiner — Melissa A Santos

(57) **CLAIM**

The ornamental design for a candle container as shown and described.

DESCRIPTION

FIG. 1.1 is a perspective view of a candle container;

FIG. 1.2 is a front view thereof;

FIG. 1.3 is a top view thereof

FIG. 1.4 is a front view thereof, shown in an open configuration;

FIG. 1.5 is a bottom view thereof

FIG. 1.6 is a front view of the upper component of the candle container, shown separately for completeness of disclosure; and

FIG. 1.7 is a perspective view thereof.

The broken lines in the figures show portions of the candle container that form no part of the claimed design.

1 Claim, 7 Drawing Sheets
